UNITED STATES PATENT OFFICE

2,484,476

SCRAPER

George J. Teigland, Wilmington, Del.

Application December 26, 1944, Serial No. 569,888

3 Claims. (Cl. 30—172)

1

My present invention, in its broad aspect, has reference to improvements in combination scraping and planing tools, and an improved blade therefore and adjustable planing surfaces, and means for quickly and accurately affecting adjustment of the respective parts, and especially of the blades, of which there are two. More particularly, it is my purpose to provide a scraping tool having detachably and adjustably carried thereon a guide frame providing a smooth planing support for the blades when the device is to be used as a planing tool, also my device is designed to present two blades at the proper angle for cutting and planing, and which is readily and quickly adjustable and is not likely to become clogged with chips or shavings and the like. My planing guide frame is adjustably and removably mounted in a unique and improved manner, and reversible. The blades are either single thickness or laminated and of reduced thickness to improve the cutting action and to facilitate sharpening. In the laminated form, the base is of low carbon steel with a hard steel layer cemented or otherwise attached thereto and providing an improved cutting edge. My invention has but few parts, is very sturdy and practical, and may be used with either wood or metal.

Other and equally important objects and advantages will be apparent from the following description and drawings, but it is pointed out that changes in the size, shape, form, construction and arrangement of parts is permissible and within the purview of my broad inventive concept, and the scope of the appended claims.

In the drawings wherein I have illustrated a preferred form of my invention—

Figure 1 is a longitudinal cross section taken on line 1—1 in Figure 2;

Figure 2 is a sectional side view, taken on the line 2—2 in Figure 1, and, partly broken away, to show the clamping rod connection;

Figure 3 is a section on the line 3—3 of Figure 1;

Figure 4 is an end view of the cutter head with the planing guide frame in one position;

Figure 5 is an end view of the cutter head with the planing guide frame reversed;

Figure 6 is a transverse section on the line 6—6 of Figure 1;

Figure 7 is an end view of the clamping plate;

Figure 8 is a top view of the clamping plate;

Figure 9 is an end view of the cutter head blade support;

Figure 10 is a side view of the cutter head blade support;

Figure 11 is a plan view of a single thickness cutter blade electroplated on one side;

Figure 12 is an end view of a single thickness cutter blade electroplated on one side;

Figure 13 is a plan view of a single thickness cutter blade case hardened on two sides;

Figure 14 is an end view of a single thickness cutter blade case hardened on two sides;

Figure 15 is a plan view of a laminated blade 10 with a low carbon steel base and a hard steel layer glued or cemented to the base to form a razor edge;

Figure 16 is an end view of the form shown in Figure 15;

Figure 17 is a hard steel solid blade in plan view, and

Figure 18 is an end view of a hard steel solid blade.

In the drawings wherein like characters of reference are used to designate like or similar parts—

The numeral 1 designates the handle of my device which may be formed of wood, plastic, or other material and which has a longitudinal bore 2 extending from its front end to a point between the ends where it communicates with a lateral channel 3. The handle has a ferrule 4 at its work end. A cutter head supporting and operating a clamping rod 5 is mounted in the bore 2 and has a threaded inner end 6 on which is carried a nut 7 accessible through the channel 3. The channel is ordinarily closed by a plug 8. Turning movement of the handle feeds the nut on the rod to adjust the rod longitudinally of the handle. The rod 5 has a beveled head 9 at its outer end. Mounted on the rod is a cutter head frame 10 having a base 11 and angularly and outwardly flared side walls 12 which are beveled as at 13; the degree of bevel being determined by the predetermined angular inclination of the blades 14 which are supported on one side on the beveled edges of the frame. These are two opposed blades 14, one extending outwardly a desired distance for proper cutting at either side of the frame. The opening 15 in the base 11 is countersunk for reversibility of the frame and clamping plate assembly. The beveled head 9 of the rod 5 is flattened at its sides as at 16 and fits into a countersunk squared slot 17 in the rectangular clamping plate 18 which has beveled edges 19 corresponding to the beveled edges 13 and cooperating therewith to clamp the blades therebetween. The frame has opposed inwardly and arcuately bent fingers 20 formed on the ends 55 of each of the side walls 12 which engage the

shoulders 21 formed by the side recesses 22 in the clamping plate 18 and the shoulders 23 formed by side recesses 24 in the blades to center the blades and clamping plate and provide a sturdy assembly. The fingers 20 extend beyond the beveled edges 13. As shown in Figures 1, 3, 4, 5, 15 and 16 the blades used with this form are of the laminated type having a low carbon steel body 25 to which are cemented, glued, or otherwise attached hard steel sections 26 to take a razor edge or a razor blade may be used in lieu of the sections 26.

As above described, my device forms a novel, practical and useful scraper, however, it is adapted for use as a planing tool by attachment of clamping elements 27 on the base of the frame 10 by means of rod 29 having a clamping head 30 and a threaded end 31 on which is a nut 32. See Fig. 6. A planing guide frame 33 is attached by clamping elements 27 to frame 10 and has articulate side sections 34 connected by opposed planing faces 35 separated by a slot 36 through which a blade extends as in Figures 1 and 4. One end is extended as at 37 to place the planing surface adjacent the blades. The planing guide frame is reversible as shown in Figure 5. My blades may be of hard steel and made solid as shown in Figures 17 and 18, or may have hard electroplating as at 38 on one side as in Figures 11 and 12, or can be hardened on both sides as at 39 in Figures 13 and 14. The types of blade may be adjusted to the use of my device under practical working conditions. The form shown in Figures 13 and 14 may have two cutting edges 40, and since the cutter blade frame is reversible, that is, to place the cutter blade frame outermost with the clamping blade innermost, my device is highly adaptable as to use.

From the foregoing, it is believed that the objects and advantages of my invention will be apparent, but it is again emphasized that interpretation of its scope should only be conclusive when made in the light of the subjoined claims.

I claim:

1. A scraping tool, comprising a handle, a reversible cutter blade frame having a base and diverging side walls extending from said base.

said side walls being provided with beveled edges, a pair of blades, one supported on each beveled edge, said blades having shoulders, arcuate fingers on the frame extending from said side walls at opposite sides thereof, the shoulders on said blades engaging said fingers to center the blades, a clamping plate having beveled edges cooperating with the beveled edges of the side walls to clamp the blades therebetween, said clamping plate having shoulders engaged and centered by the fingers from said side walls, a supporting rod means extending through said clamping plate and base for securing the same together and to the handle.

15 2. The invention as defined in claim 1 wherein
the arcuate fingers rise from the ends of the
frame and extend in advance of the beveled edges
of the frame, and wherein the frame is reversible
and the blades are supported at an angle to the
20 side wall of the frame.

3. The invention as defined in claim 1 wherein the rod is threaded into a nut carried by the handle to be adjustable lengthwise of the handle and wherein a ferrule is provided between the
25 handle and frame.
